UNITED STATES PATENT OFFICE.

JOHN A. CAMPBELL, OF TRENTON, NEW JERSEY, ASSIGNOR TO TRENTON POTTERIES COMPANY, OF TRENTON, NEW JERSEY.

DESIGN FOR A LAVATORY.

42,457.

Specification for Design.

Patented May 7, 1912.

Application filed June 9, 1910. Serial No. 566,112. Term of patent 7 years.

To all whom it may concern:

Be it known that I, JOHN A. CAMPBELL, a citizen of the United States, residing at Trenton, in the county of Mercer, State of New Jersey, have invented a new, original, and ornamental Design for Lavatories, of which the following is a specification, reference being had to the accompanying drawing, forming a part hereof.

The figure is a perspective of the lavatory showing my new design.

I claim:

The ornamental design for a lavatory as shown.

JOHN A. CAMPBELL.

Witnesses:

WILLIAM G. CRUSER,
EDWARD C. STOVER.
